CONVERTIBLE HIGH-LOW BABY CHAIR

Leonard W. Yost, Atwater, Calif.

Application August 2, 1949, Serial No. 108,089

2 Claims. (Cl. 155—38)

This invention is directed to, and it is an object to provide, a novel combination baby chair; the same being arranged for ready and convenient manual adjustment to serve as a high chair, a walker, or a push-type stroller.

Another object of the invention is to provide a combination baby chair, as above, which includes a tray adapted to be mounted between the arm rests in a novel manner, when the device is in use.

A further object of the invention is to provide a combination baby chair wherein the several parts thereof are connected together in foldable relation whereby the device may be collapsed to a compact position for ease of carrying or storage when not in use.

An additional object of the invention is to provide a combination baby chair which embodies a novel push handle for use when the device is adjusted as a stroller such push handle being folded to an out-of-the-way position when not in use.

It is also an object of the invention to provide a combination baby's chair which is designed for use and economy of manufacture; the chair being sturdy, and stable in its several positions of use.

A further object of the invention is to provide a practical and reliable combination baby chair, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the combination baby chair as adjusted for use as a high chair.

Fig. 2 is a sectional elevation showing the device adjusted for use as a stroller; the same position of adjustment, but with certain of the parts in altered positions, adapting the device for use as a walker.

Fig. 3 is a side elevation of the device as folded or collapsed for transport or storage.

Fig. 4 is a plan view of the device as adjusted for use as a walker.

Fig. 5 is a fragmentary rear end view showing mainly the seat structure and the extensible or telescopic push handle as arranged therewith.

Fig. 6 is a fragmentary transverse section on line 6—6 of Fig. 2.

Fig. 7 is a fragmentary transverse section on line 7—7 of Fig. 1.

Referring now more particularly to the char-

acters of reference on the drawings, the novel combination baby chair comprises, preferably of metallic structure, a rectangular base frame 1 of open construction; such base frame 1 being fitted, adjacent the rear corners and outside thereof, with transversely spaced rear wheels 2.

Transversely spaced caster wheels 3 support the base frame 1 at the front inwardly and slightly to the rear of the corresponding corners.

10 The base frame 1 is thus adapted to be supported, closely adjacent and for movement along the ground, by the wheels 2 and 3.

The base frame 1 is adapted to be supported from the ground at a relatively higher elevation by a plurality of corner legs 4 pivoted at their upper ends, as at 5, to the corners of the base frame 1. The corresponding legs 4 at each side of said frame are adapted to swing upwardly and inwardly to folded position; said corresponding legs when folded being adapted to nest as shown in Fig. 6; one of said legs being tubular, while the other is substantially semi-circular, as shown, in order to accomplish the above nesting.

25 The corresponding legs 4 at each side of the base frame 1 are adapted to be rigidly maintained in their depending operative position by a pivotally connected brace unit 6 which extends between such legs; such brace unit 6 including a slip-latch 7 whereby the brace unit and consequently the related legs 4 may fold upwardly to an out-of-the-way position with respect to the rear wheels 2 and 3. When so folded, the legs 4 and brace units 6 lie above the low points of the wheels 2 and 3.

30 Each pair of corresponding legs 4 is releasably held in raised or folded position by catch means which includes a pin 8, on the lowermost leg of each pair, engaged in a spring catch 9 on the uppermost leg of each pair (see Fig. 6).

40 A folding chair unit, indicated generally at 10, is disposed above the base frame 1 and includes a seat frame 11, an upstanding cross member 12 at the rear of the seat frame, and a back 13 which projects above the cross member 12, being affixed to the latter by a piano hinge 14 for forward and downward folding movement. The back 13 is rearwardly flanged about its top and side edges, as at 15, to strengthen the back 13 and also to provide a pocket for reception of the push handle, as hereinafter described.

45 At each side thereof the folding chair unit 10 is supported, from the base frame 1, by a pair of longitudinally spaced, supporting links 16, which are pivotally connected between corresponding sides of said base frame 1 and the seat frame 11.

When the device is in use the supporting links 16 are maintained in an upright position by a releasable latch bar 17 of pin and slot type which extends diagonally between, and is pivoted to, the base frame 1 and one of said links 16 at each side of the chair.

By releasing the latch bars 17 the folding chair unit 10 may be lowered from its raised position of use, as in Fig. 1 or 2, to a lowered non-working position, as in Fig. 3.

The folding chair unit 10 includes transversely spaced, forwardly projecting arm rests 18 pivoted at the rear ends to opposite sides of the back 13; each such arm rest 18 being supported from the seat frame 11 by a pair of pivotally connected, upstanding links 19 in spaced relation and aligned with respect to corresponding ones of the links 16.

The folding chair unit 10 is normally held against folding or collapse by a latch bar 20 of 20 pin and slot type which extends diagonally between, and is pivoted to, the seat frame 11 and one of the links 19 at each side of the chair unit. Upon release of the latch bars 20 the chair unit 10 is foldable from its erected position, as in Figs. 1 and 2, forwardly and downwardly with respect to the seat frame 11, until the parts lie in non-working collapsed position, as in Fig. 3.

By upward folding of the legs 4, and downward folding of the links 16 and 19, all of the 30 parts of the device collapse to their respective positions, as shown in Fig. 3, and wherein the device may be transported or stored.

The seat frame 11 supports a seat 21, formed—in the forward portion thereof—with a pair of transversely spaced leg openings 22; said seat 21, including the leg openings 22, being covered by a cover plate 23 hinged at its rear edge, as at 24, for upward and rearward swinging to an open position lying against the back 13. When the cover plate 23 is in its "down" position, a baby sits thereon with its legs overhanging the front edge of the seat 21, whereas when said cover plate 23 is in open position the baby rests on the seat 21 with its legs depending through the openings 22, for walking.

For use as a high chair, the device is adjusted as shown in Fig. 1, with the legs 4 in depending base frame supporting position, and with the chair unit 10 unfolded and supported in spaced relation above the base frame 1. This supports the baby at proper height for convenient feeding, which feeding is enhanced by the use of a tray 25 which spans between, and is connected to, the arm rests 18 in the following manner:

As shown in Fig. 7, one end of the tray is hinged to the adjacent arm rest 18, as at 26, for upward and lateral swinging motion, to permit of placement of the baby in, or its removal from, the chair unit.

The hinge 26 is detachable from the adjacent arm rest 18, to permit of removal of the tray 25, by fitting such hinge with a bar 27 which engages in a longitudinal holding channel 28 formed on said adjacent arm rest 18 and open to the front. The bar 27 is slid out of the open front end of the channel 28 when it is desired to detach the tray.

At the end opposite the hinge 26 the tray 25 is detachably, and longitudinally adjustably secured, to the corresponding arm rest 18 by a depending tongue 29 which projects through a slot 30 in the adjacent arm rest 18; there being a spring-pressed pin 31 which engages selectively in one of a row of holes 32 in said tongue. The

pin 31 is mounted on a leaf spring 33, which not only urges the pin 31 toward the tongue 29, but also provides for finger engagement to retract said pin.

When the device is to be used as a walker the legs 4 are folded upwardly to their out-of-the-way position, and the wheels 2 and 3 rest on the ground.

The cover plate 23 is then swung rearwardly and upwardly to its open position, as shown in dotted lines in Fig. 2, whereby the baby is placed on the seat 21 with its legs depending through the openings 22 for ground engagement, and as is desirable towards teaching the baby to walk.

When the device is used as a stroller the baby is placed in the chair unit 10, either with the cover plate 23 in its lowered position, with the baby's legs overhanging the front edge of the seat 21, or with said plate in its open position with the baby's legs extending through the openings 22.

To control the device, as a stroller, the following push handle arrangement is provided:

25 A generally inverted V-shaped swing frame 34 is pivoted between the side flanges 15 adjacent the lower edge of the back 13; such swing frame being fitted, at the apex, with an extensible or telescopic push handle 35.

The swing frame 34 is maintained in a position of use; i. e. at an upward and rearward incline, by an over-dead-center link unit 36 which connects between the back 13 and the swing frame 34 adjacent its apex.

With the above described push handle the device can be conveniently manipulated as a stroller.

When not in use the push handle 35 is retracted; the link unit is broken downwardly; and the swing frame 34 and said handle are folded forwardly into the pocket formed by the edge flanging 15 of the back 13.

For storage the device is collapsed in the manner shown in Fig. 3.

45 To facilitate manual carrying of the device as so folded, a suit-case type handle 37 is secured to the cross member 12 centrally of the ends of the latter; the device thus being carried in an on-edge position.

The described device provides a very convenient, practical and reliable combination chair for a baby; the chair being easy to manually adjust between its selective positions, and when in use being stable and effective for the intended purposes.

55 From the foregoing description it will be readily seen that there has been produced such a device as substantially fulfills the objects of the invention, as set forth herein.

60 While this specification sets forth in detail the present and preferred construction of the device, still in practice such deviations from such detail may be resorted to as do not form a departure from the spirit of the invention, as defined by the appended claims.

65 Having thus described the invention, the following is claimed as new and useful, and upon which Letters Patent are desired:

70 1. A combination baby chair comprising a base frame having a chair supported thereby, the frame including longitudinal side members, wheels mounted on the frame for ground engagement, and a pair of legs pivoted on each side member at the ends of the latter for movement between a depending position and a folded position alongside the member, one leg of each pair

5

being of substantially circular form in section and the other leg of each pair being substantially semi-circular in section and facing in a direction and of a size to receive said one leg therein when the legs are in said folded position.

2. A structure, as in claim 1, with releasable holding means for the folded legs comprising an element on said other leg adjacent its normally lower end, and a cooperating element on the one leg adjacent its pivoted end.

LEONARD W. YOST.
